DESIGN FOR A MOTOR VEHICLE RADIATOR SHIELD

Jacob F. Martin, Bellevue, Ohio

Application January 18, 1935, Serial No. 54,910

Term of patent 3½ years

To all whom it may concern:

Be it known that I, Jacob F. Martin, a citizen of the United States of America, residing at Bellevue, Huron County, Ohio, have invented a new, original, and ornamental Design for Motor Vehicle Radiator Shields, of which the following is a specification, reference being had to the accompanying drawing, forming part thereof.

Fig. 1 is a front elevation of the motor vehicle radiator shield showing my new design;

Fig. 2 is a view from the right of Fig. 1; and
Fig. 3 is a plan view of the shield of Fig. 1.

I claim:—

The ornamental design for a motor vehicle radiator shield substantially as shown.

JACOB F. MARTIN.
